UNITED STATES PATENT OFFICE.

CHARLES G. CURTIS, OF NEW YORK, N. Y.

MARINE STEAM-TURBINE.

1,008,529.

Specification of Letters Patent. Patented Nov. 14, 1911.

Application filed November 18, 1910. Serial No. 593,154.

To all whom it may concern:

Be it known that I, CHARLES G. CURTIS, a citizen of the United States, residing at New York city, in the county and State of New York, have invented a certain new and useful Improvement in Marine Steam-Turbines, of which the following is a specification.

The object I have in view is to simplify and cheapen the construction and repair, and also to increase the efficiency, of marine steam turbines, particularly those having initial jet impulse stages.

In the employment of steam turbines for the propulsion of ships, the high speed of the turbines makes necessary or desirable the relieving of the thrust blocks, so far as possible, of the thrust due to the propellers. In marine steam turbines of the axial flow type, steam pressures are available, exerted longitudinally of the propeller shafts, which can be employed to neutralize the propeller thrust. The utilization of the steam pressure to neutralize the propeller thrust has created a limitation upon the design of marine steam turbines, especially of those having initial jet impulse stages, resulting in complication of parts and excessive length and cost of the turbine. In the design of impulse marine steam turbines, in order to obtain the large number of steam expansions necessary to give the required low shaft speed with high efficiency, the practice has been to provide at the steam admission end of the turbine a considerable number of wheel stages with their accompanying diaphragms to separate the pressures carried in the different stages. This has been necessary in order to bring the pressure down to a point so that when the steam is applied to a final drum pressure stage, the difference in pressure on the drum head will give a backward thrust on the shaft which will equal approximately the forward thrust of the propeller. This pressure must be low, because the area of the drum head is large, and because in steam turbines of the impulse type, or those having initial jet impulse stages, an additional backward thrust results from the fact that the shaft at the ends of the turbine casing is usually stepped down or reduced in diameter to give a practical size for effective packing by means of stuffing boxes or packing glands. This construction produces an area subject to the high pressures existing

in the early wheel stages which exerts a thrust opposed to the propeller thrust, due to the fact that at the other end of the turbine casing where the shaft is similarly stepped, the corresponding area is subject to the exhaust or terminal pressure. This thrust produced by the reduction in size of the shaft at the ends of the turbine casing, and which will herein after be referred to as the "shaft-thrust", may be as great as forty per cent. of the propeller thrust, or even more, and hence reduces the amount of propeller thrust, which must be neutralized by the head of the final drum stage. The necessity which thus arises for employing a considerable number of wheel stages results in an increase of complication and expense in construction, and also in an increase in the length of the turbine, due to the numerous diaphragms and steam spaces required. The difficulty and cost of repair are also increased on account of the inaccessibility of the diaphragms and the bushings carried by them, which reduce the steam leakage between the wheel stages.

By my present invention two or more drum pressure stages are employed having steam tight heads adapted to withstand a considerable pressure difference without change of shape, and one or more of these drum stages is or are reversed so as to produce a thrust in the same direction as the propeller thrust. By properly proportioning the steam passage areas through the drum stages, so as to secure the proper pressure drop between the two ends of each drum stage, and by having each drum head of the proper comparative area, the aiding thrust of the reversed drum stage or stages will bear such a relation to the opposing thrust of the direct drum stage or stages, that, taking into consideration the opposing shaft-thrust, there will be produced a thrust opposing the propeller thrust which will substantially neutralize or balance the propeller thrust, or reduce the resultant thrust which must be carried by the thrust block to an entirely practicable amount. The turbine thrusts, which are dependent upon the steam pressure, vary with the load, as likewise does the propeller thrust, but not in exactly the same ratio. The difference in this respect, however, is not great enough to prevent the practical balancing of the propeller thrust by the turbine thrust at all substantial power. The drum stages may

be constructed so as to operate on the impulse or on the reaction principle. If they operate on the latter principle, the blade thrust, due to differences in pressure between the entrance and exit edges of the moving blades, will also have to be taken into consideration as an element in the construction of the turbine.

By the employment of the reversed drum pressure stages, I am enabled to largely reduce the number of the initial wheel stages, and the accompanying diaphragms, steam spaces, etc. Two or three such wheel stages will probably be found sufficient for the objects which they subserve in my improved turbine, although more than three or only one may be employed, depending upon the power to be developed and the steam pressure to be used. These objects are to secure by the nozzles of the first wheel stage a considerable reduction in pressure to a point which can be practically controlled as to leakage by packing around the shaft, and to reduce the pressure and increase the volume of the steam before reaching the first drum stage so that the complete annular admission of steam at the drum stage can be secured with blades of such a depth (radially) that the loss by tip clearance leakage will be reduced to a permissible percentage. In the wheel stages, although the volume of the steam is small at this point, the buckets can be made of the desired radial depth because of the fact that a partial peripheral admission of the steam (*i. e.*, "jet" admission) is employed in these stages. The principle of neutralizing the propeller thrust already set forth may also be applied to the reversing turbine, but with the simple and low efficiency forms of reversing turbines now employed, this is not necessary, since a small number of wheel stages can be employed, and a final drum pressure stage can be used whose diameter will be so reduced that the area presented by the drum head will give the necessary pressure to reduce the resultant thrust upon the thrust block to a practicable amount.

Another feature of my present invention consists in providing a construction which will give accessibility to the diaphragm bushings or packings so that they can be renewed or repaired without removing the shell or casing of the turbine. This is accomplished by such an arrangement of the parts that spaces are provided adjacent to the diaphragms large enough to permit the removal and replacement of the bushings or packings in sections without the disturbance of other parts, which spaces, in the case of high power turbines, may be large enough to admit the body of a workman. Access is given to these spaces by means of man-holes or hand-holes in the heads and sides of the casing, and if necessary, in one or more dia-

phragms, which man-holes or hand-holes are provided with suitable covers, readily detachable. In cases where pipes are employed exterior to the casing, to carry the reverse steam flow for one or more reversed drum stages, these pipes may be connected with the enlarged spaces adjacent to the diaphragms, and the removal of the pipes from their connections with the casing will expose openings, through which access to the diaphragm bushings may be had. With the small number of wheel stages and diaphragms which can be used when reversed drum stages are employed, such enlarged spaces at the diaphragms can be provided without undue increase in the length of the turbine. This feature of accessibility to the diaphragm bushings is also applicable to the reversing turbine.

The features of the invention herein set forth are applicable to various turbine arrangements, some of which will form the subject of separate applications for patents. In the present case, they are shown in the drawing applied to a simple form of turbine, in which all the elements, including the reversing turbine, are mounted upon a single shaft, and inclosed by the same casing.

In the drawing, Figure 1 is an elevation with the upper half in longitudinal section of a simple form of turbine embodying my invention. Fig. 2 is a plan view on a smaller scale of the turbine in outline showing the relation thereto of the propeller and the thrust block. Fig. 3 is an elevation of the forward head of the turbine with the upper half in section on the line 3-3 in Fig. 1; and Fig. 4 is a vertical lateral section of the turbine on the line 4-4 in Fig. 1.

The rotating elements are mounted upon a shaft 5, while the stationary elements are attached to a cylindrical casing whose sides are indicated at 6, and whose forward and aft heads are indicated by 7 and 8. At the forward end of the casing are two wheels 9, 10, which are mounted upon steps formed on the shaft, which is reduced in diameter at the point 11, where it passes through the stuffing box 12. The difference in diameter between the shaft at 11 and the hub of the wheel 10 at the point 13 produces a thrust area subjected to the first stage pressure, which opposes the propeller thrust. The wheels 9 and 10 carry preferably, each a number of rows of moving buckets separated by stationary intermediate buckets carried by the casing. The steam in the steam chest 14 passes through nozzles 15, which nozzles convert pressure into velocity, and deliver the steam to a part of the periphery of the wheel 9. The steam pressure on opposite sides of the wheel 9 is the same. Between the wheels 9 and 10 is the diaphragm 16, carrying the second stage nozzles 17, which produce a further conversion

of pressure into velocity and deliver the steam to a part of the periphery of the second wheel 10, which operates like the first wheel 9 on the impulse principle, and has the same pressure on opposite sides. The diaphragm 16 is supported by the casing, and is subject to the difference in pressure between the first and second wheel stages. Where it surrounds the shaft it is provided with a diaphragm bushing 18, which may be any suitable form of diaphragm bushing, or by reason of the accessibility for replacement, may be some form of packing, making actual contact with the shaft or the wheel hub. The space 19 in front of the diaphragm 16 is made large enough to permit the removal and replacement in segments of the diaphragm bushing or packing 18 without removing the casing or the further separation of the wheels. Access is given to the space 19 by means of covered man-holes or hand-holes 20 (one or more) in the casing head 7, and through one or more openings 21 in the web of the wheel 9. Access to the bushing of the diaphragm following the first wheel stage is important, because the first stage pressure is present at this bushing and the steam leakage at this point is greater than at any succeeding diaphragm. The diaphragm 16 may also be provided with covered man-holes or hand-holes 22 (one or more) to give access through one or more openings 23 in the web of wheel 10 to the space 24 in front of diaphragm 25, which in the form of turbine illustrated, closes the interior of the casing following the second wheel stage and preceding the first drum stage in order that the steam flow through the first drum stage may be reversed. The drum 26 of the first drum stage is supported upon the shaft by a steam tight head 27 having the proper strength to resist the steam pressure difference to which it is subjected without change of shape. The drum 26 carries a number of annular rows of moving buckets, separated by stationary intermediate buckets carried by the casing, and the flow of the steam through these buckets is a forward one from the space 28 toward the head of the machine, instead of a flow toward the aft end of the machine, as in the wheel stages. The admission of steam to the buckets of the first drum stage is a complete peripheral admission, and the buckets of this drum stage may operate upon the impulse principle or upon the reaction principle. The result in either case is a considerable reduction in pressure between the space 28 aft of the head 27 and the space 29 forward of that head.

To secure the reversal of the steam flow, the steam may be conducted after leaving the wheel stages from the space 24 in front of the diaphragm 25 to the space 28 by

means of pipes 30 exterior to the casing. The thrust produced by the difference in steam pressure upon the head 27, it will be seen, is in a forward direction, the same as the propeller thrust. Aft of the space 28 is another diaphragm 31 supported by the casing and having a bushing or packing at its inner opening surrounding the shaft and accessible in the space 28. This diaphragm 31 closes the space between the casing and the shaft between the first and second drum stages. The spaces 24 and 28, which are connected by the exterior pipes 30, are large spaces, which in a high power turbine, would be large enough to admit the body of a workman, and by removing any one of the pipes 30, a workman can enter these spaces to repair or replace the bushings or packings carried by the diaphragms 25 and 31. The steam, after passing through the first drum stage, enters an annular space 32 in the shell, which is connected by channels 33 with the space 34 back of the diaphragm 31, which space forms the entrance to the second drum stage. The drum 35 of the second drum stage is supported from the shaft in part by means of a steam tight head 36, which is formed to withstand the difference in pressure to which it is subjected without change of shape, its aft or rear side facing a space 37, which is connected with the exhaust 38, so that the head 36 is subjected on its forward side to the admission pressure of the second drum stage, and on its aft side to the exhaust pressure. The hubs of the drum heads 27 and 36 meet on the shaft and are surrounded by a strain ring 48 which fits over shoulders on the hubs of 27 and 36. This strain ring forms a true surface, facing the bushing of the diaphragm 31, and also tends to prevent separation of the heads 27 and 36 which are subjected to steam pressures tending to separate them. The drum 35 of the second drum stage carries, like that of the first drum stage, a number of annular rows of buckets separated by intermediate annular rows of buckets carried by the casing, and operating on the impulse or reaction principle, so that there is a considerable difference in steam pressure between the entrance and exit ends of the stage. The areas of the heads 27 and 36 are such relative to the steam pressures maintained in the steam spaces on the opposite sides of these heads and relative to the shaft-thrust areas and the steam pressures acting upon them, that the thrust produced by the pressure on the head 36 of the second drum stage opposing the propeller thrust, aided by the shaft-thrust, and opposed by the forward thrust produced by the head 27 of the first drum stage, results in the practical neutralization of the propeller thrust at all substantial powers. The slight resultant thrust, if any, one way or the other, is taken by the thrust 130

4 block 39 (Fig. 2). In Fig. 2 the propeller 40 is also shown mounted on the shaft 5.

As showing the balancing of the propeller thrust in accordance with my invention, 5 take, for example, a 2-shaft 25-knot cruiser of 22,000 S. H. P. at about 360 R. P. M. with a turbine such as illustrated on each shaft developing at full power 11,000 S.H.P. Under these conditions, with a propulsive 10 efficiency of 60%, the thrust of each propeller will be 86,000 lbs. at full power and 26,500 lbs. at 20% power. In this example, the moving buckets of the drum stages are considered as operating on the impulse principle. 15 In the steam chest supplying the first stage nozzles, the steam pressure may be, for illustration, 200 lbs. (absolute) and 40° F. superheat and the exhaust pressure of the turbine 28 inches of vacuum or about one 20 pound absolute, the latter pressure acting on the rearward side of the second drum stage. Let us assume that the first stage pressure, 25 acting on the shaft thrust area, is designed to be at full power 100 lbs. (absolute) and the second wheel stage pressure 72.5 lbs. 30 giving a pressure on the admission side of the first drum stage of about 72 lbs. This pressure being fixed, and a convenient pitch diameter for the two drum stages being selected, say, for example, 8 feet and 9 feet 35 respectively, the pressures necessary on the two sides of the drum heads 27 and 36 to balance the thrust can be readily calculated when the areas subject to the steam pressures 40 are known. The shaft thrust area which receives the first stage pressure already assumed to be 100 lbs. absolute, is found by computing the area of the annulus formed by the smallest and largest diameters of the 45 shaft subject to this pressure, which may be, for example, 22 inches and 32 inches respectively, giving an area of 424 square inches. The areas of the high and low pressure sides of the first or reverse drum stage will be 50 found to be respectively 6,104 square inches and 6,434 square inches, and the areas of the high and low pressure sides of the second or direct drum stages will be found to be respectively 8,027 square inches and 8,545 55 square inches. Starting with a steam pressure of 72 lbs. on the high pressure side of the first drum stage, and with an exhaust pressure of 1 lb., the pressures necessary to be maintained on the low pressure side of the first drum stage and on the high pressure side of the second drum stage to balance the thrust under the conditions assumed will be found to be about 34 lbs. This pressure will be maintained by properly proportioning 60 the area of the blade gap at the admission end of the second drum stage. The steam pressures, therefore, acting on the shaft thrust area and on the high and low pressure sides of the two drum stages at the 65 full power of the turbine will be respectively

in pounds absolute about 100, 72, 34.25, 34 and 1. At 20% power, produced by reducing the steam flow, the corresponding steam pressures in pounds absolute which will be produced by the same areas of steam passages will be 25, 21.6, 10.3, 10.2 and 0.74. These dimensions and steam pressures give the following thrust in pounds at full power and 20% power respectively:

	Full power thrust.		20% power thrust.		75
	Forward.	Aft.	Forward.	Aft.	
Propeller	86,000		26,500		
Shaft area		42,400		10,600	80
First drum	440,000	220,300	181,900	66,300	
Second drum	8,500	272,900	6,300	81,900	
Total thrust	584,500	535,600	164,600	158,800	
Unbalanced thrust		1,100	5,800		

From this table it will be seen that at full power there is an almost exact neutralization of the thrusts, including the propeller thrust, and it is evident that by further refinement, an exact neutralization could be secured. At 20% power, the unbalanced forward thrust indicated by the table is so small that it can be readily taken care of by the thrust block. As shown by the table, when the proportions are those specifically stated, the tendency is for the unbalanced thrust to approach in amount the propeller thrust at low powers, but this is not important because the unbalanced thrust is small and can be readily taken care of by a thrust block of convenient size. At all substantial powers the propeller thrust is wholly or largely neutralized. It is evident that the areas and steam pressures may be proportioned so that the point of exact neutralization or, of minimum unbalanced thrust will be at either end of the power range, or at some intermediate point, or so that at all powers there will be a resultant thrust in the same direction on the thrust block.

The reversing turbine, which is shown to the left in Fig. 1, is of the simple construction already referred to, having two wheel stages 41, 42 and one intermediate diaphragm 43, to the bushing or packing of which access is had by covered man-holes or hand-holes 44 in the casing head 8 and openings 45 in the wheel 41, in the same manner as explained in connection with the diaphragm between the first and second wheel stages at the head of the turbine. The second wheel stage of the reversing turbine delivers the steam directly to a drum stage 46 which discharges into the exhaust 38. The drum stage 46 of the reversing turbine is made of smaller diameter than the drum stages of the go-ahead turbine, and its pressure head 47 has a smaller area so as to approximately neutralize the propeller thrust under the conditions of operation of the reversing turbine. This also brings the

discharge of steam from the two turbines out of line so that there is a free passage for the steam from the ahead turbine into the exhaust.

5. What I claim is:

1. The combination with the propeller and propeller shaft of a ship, of a steam turbine directly connected with said propeller shaft, said turbine having reversed drum pressure stages exerting thrusts in opposite directions and producing a resultant thrust opposed to the propeller thrust and varying with the load so as to wholly or largely neutralize the propeller thrust at all substantial powers, substantially as set forth.
  2. The combination with the propeller and propeller shaft of a ship, of a steam turbine directly connected with said propeller shaft, said turbine having one or more initial jet wheel stages and reversed drum pressure stages, the latter exerting thrusts in opposite directions and producing a resultant thrust opposed to the propeller thrust and varying with the load so as to wholly or largely neutralize the propeller thrust at all substantial powers, substantially as set forth.
  3. The combination with the propeller and propeller shaft of a ship, of a steam turbine directly connected with said propeller shaft, said turbine having one or more initial jet wheel stages, a reversed drum pressure stage producing a thrust in the same direction as the propeller thrust and a direct drum pressure stage producing a thrust opposed to the propeller thrust and greater than the thrust of the reversed drum stage, whereby a resultant turbine thrust will be produced opposing the propeller thrust and varying with the load so as to wholly or largely neutralize the propeller thrust at all substantial powers, substantially as set forth.
  4. The combination with the propeller and propeller shaft of a ship, of a steam turbine directly connected with said propeller shaft, said turbine having a drum pressure stage at the exhaust end of the turbine producing a thrust opposed to and exceeding the propeller thrust and one or more preceding drum pressure stages neutralizing in part the thrust of the final drum stage and producing a resultant thrust opposed to the propeller thrust and varying with the load so as to wholly or largely neutralize the propeller thrust at all substantial powers, substantially as set forth.
  5. The combination with the propeller and propeller shaft of a ship, of a steam turbine directly connected with said propeller shaft, the shaft within the turbine being reduced in size at its ends and said turbine hav-
- ing one or more initial jet wheel stages the steam pressure in which acts on the shaft to produce a thrust opposed to the propeller thrust, and reversed drum pressure stages exerting thrusts in opposite directions and producing with the shaft thrust a resultant thrust opposed to the propeller thrust and varying with the load so as to wholly or largely neutralize the propeller thrust at all substantial powers substantially as set forth.
6. In a steam turbine, the combination with the casing, the shaft and the rotating bucket elements divided into stages in which different steam pressures are maintained, diaphragms supported by the casing for separating the stages having bushings or packings surrounding the shaft, spaces between the diaphragms and rotating elements for enabling the diaphragm bushings or packings to be repaired or replaced without dismantling the turbine, and means for giving access to such spaces, substantially as set forth.
7. In a steam turbine, the combination of wheel stages located adjacent the head of the casing, a diaphragm separating the wheel stages and separated from the first wheel by a space large enough to permit manipulation of the diaphragm bushing or packing and one or more openings in the head of the casing and in the first wheel to give access to this space, the head opening or openings being covered, substantially as set forth.
8. In a steam turbine, the combination with a diaphragm separating stages, of one or more covered openings in the diaphragm for giving access to interior spaces of the turbine, substantially as set forth.
9. In a steam turbine, the combination of a drum stage, diaphragms separating the drum stage from preceding and succeeding stages, a working space on one side of each diaphragm and openings in the sides of the casing giving access to such spaces, substantially as set forth.
10. In a steam turbine, the combination with the shaft and casing, of a plurality of wheel stages and a plurality of drum stages, diaphragms separating the several stages and bushed or packed around the shaft, working spaces separating the diaphragms from rotating elements and covered openings in the heads and sides of the casing for giving access to such working spaces, substantially as set forth.

This specification signed and witnessed this 15th day of November, 1910.
